His ATTORNEY'S

UNITED STATES PATENT OFFICE.

LELAND A. PHILLIPS, OF ROCHESTER, NEW YORK, ASSIGNOR TO PHILLIPS RIBBON & CARBON COMPANY, OF ROCHESTER, NEW YORK, A CORPORATION OF NEW YORK.

REELING-MACHINE.

1,309,367.

Specification of Letters Patent.

Patented July 8, 1919.

Application filed July 29, 1918. Serial No. 247,097.

To all whom it may concern:

Be it known that I, LELAND A. PHILLIPS, a citizen of the United States, residing at Rochester, in the county of Monroe and 5 State of New York, have invented certain new and useful Improvements in Reeling-Machines; and I do hereby declare the following to be a full, clear, and exact description of the invention, such as will enable 10 others skilled in the art to which it appertains to make and use the same.

My present invention relates to winding and reeling and has for its object to provide a simple, inexpensive and convenient machine for office use, through the medium of which fresh lengths of typewriter ribbon may be wound upon the small reels, or spools, used in the inking mechanism of typewriting machines, the ribbon being supplied in bulk rolls and transferred to spools as required. A further object of the invention is to provide a machine of few parts that can be successfully operated by unskilled persons. To these and other ends 25 the invention resides in certain improvements and combination of parts all as will be hereinafter more fully described, the novel features being pointed out in the claims at the end of the specification.

30 In the drawings:

Figure 1 is a front view of a reeling machine constructed in accordance with and illustrating one embodiment of my invention;

35 Fig. 2 is an enlarged sectional view taken substantially on the line 2—2 of Fig. 1, and

Fig. 3 is a fragmentary elevation of the rear side of the machine.

40 Fig. 4 is a sectional view showing a different from of reel held in position.

Similar reference numerals in the several views indicate the same parts.

Referring more particularly to the drawings, 1 indicates a frame or standard having a jaw 2 at its base carrying a thumb screw 3, by means of which the machine may be clamped to the edge of a shelf or table 4. At the top of the frame is a bearing 5 45 for a laterally extending shaft 6 having an enlarged thrust collar or shoulder 7 at one end, while at the other end and on the other side of the frame the shaft carries a fixed pinion 8 that is riveted thereon in the present 50 instance. These parts 7 and 8 prevent longi-

tudinal movement of the shaft and the former is provided with a recess 7' on its outer face and is cut away at 7" for a purpose to be described. On the same side of the frame and meshing with the pinion 8 is a gear 9 rotatable on a stud 10 and provided with a crank handle 11 constituting means for driving the shaft 6. The shaft 6 is threaded at 12, preferably with a left-hand thread, to receive a screw 13 terminating in a conical knurled head 14.

In the operation of the machine a typewriter ribbon spool or reel indicated at 15 is placed on the screw 13, and the latter screwed into the shaft so that the reel is held on the shank of the screw against the thrust shoulder 7 by the head 14. The latter is made conical to permit it to properly center reels having different sized central openings. When these openings are larger than the shank of the screw the conical head will not only center the reel but the engagement of the inner face of the reel with the shoulder 7 will maintain it in position.

The ribbon to be wound is furnished in a reel 16 having a small wooden core 17. It is supported and caused to track properly with reference to the receiving wheel 15 by a fixed spindle 18 projecting laterally from the frame 1 in parallelism to the shaft 6. 80 At its base is a fixed face plate 19. The roll 16 is held in rotatable engagement with this face plate by a friction or spring nut 20 that is tightened against a washer 21 on the outer side of the roll. The spring nut 20 85 has perforated spring ends 22 that bite against the spindle 18 and lock the nut in position whenever released from the pressure of the fingers.

The remainder of the operation of the 95 machine will be understood. The roll 16 may be left thereon until used up, and a new roll can be easily and quickly applied by pulling off the nut 20 and sliding it on to the spindle. The face plate 19 holds the 100 roll accurately in the proper plane to track with the receiving reel, and as it does not rotate it does not require to be carefully machined.

When used in connection with a reel in 105 which the axial aperture does not extend through the reel 15, the screw 13 which is approximately the size of said aperture is inserted in the opposite direction through the shaft and a pin 30 provided on said reel 110

enters the perforation 7' on the shoulder 7 while the lug or trip 31 employed on reels of this kind is accommodated in the cut away portion 7x.

5 It will thus be seen that the machine is adapted to handle any of the usual spools or reels in use.

Having described my invention what I desire to secure by Letters Patent is:

10 1. In a ribbon reeling machine, the combination with a frame, a laterally extending shaft having a bearing therein and provided with a thrust shoulder, means comprising a conical headed member for concentrically securing to said shaft against said shoulder reels of various dimensions, driving means for said shaft, a spindle on said frame parallel with said shaft provided with a thrust shoulder in the plane of the 15 shoulder of said shaft, and retaining means for holding a reel on said spindle.

20 2. In a reeling machine, a frame, a rotatable shaft thereon having a thrust shoulder provided with an eccentric engaging means, 25 a reel holding member comprising a conical

head adapted to be concentrically attached to said shaft at either end thereof for securing reels of varying dimensions to said shaft against said shoulder, driving means for said shaft, and a spindle on said frame 30 for rotatably holding a reel in the plane of a reel on said shaft.

3. In a ribbon reeling machine a rotatable ribbon reel holder comprising a rotatable shaft, having an axial threaded aperture, 35 and a thrust shoulder thereon, in combination with a reel holding member threaded to enter the threaded aperture and having a conical head thereon, to center and hold the reel against the shoulder.

4. In a ribbon reeling machine a rotatable ribbon reel holder comprising a rotatable shaft, having an axial threaded aperture extending through it and a thrust shoulder thereon provided with an aperture eccentric 45 to the axis of rotation in combination with a reel holding member comprising a threaded rod having a conical head.

LELAND A. PHILLIPS.
